METHOD FOR ANALYZING WHITE FUMING NITRIC ACID

John D. Clark, Kinnelon, N. J.

Application December 1, 1953, Serial No. 395,626

3 Claims. (Cl. 324—30)

(Granted under Title 35, U. S. Code (1952), sec. 266)

The invention described herein may be manufactured by or for the Government of the United States of America for governmental purposes without the payment of any royalties thereon or therefor.

This invention relates to a method and apparatus for analyzing white fuming or anhydrous nitric acids, and especially relates to the analysis of the acids outside the laboratory and by relatively unskilled operators.

As far as is known, no "field method" for the analysis of white fuming nitric acid has been provided. The laboratory methods are unsuitable for field work, requiring standard solutions, fragile glassware and skilled manipulation.

One object of this invention is to provide a method and apparatus usable in the range of 0 to 5% water content and 0 to 2.5% NO_2 content of the acid.

Another object of this invention is to maintain an accuracy up to 0.1% in H_2O content and 0.1% in NO_2 content.

Another object of this invention is to provide analysis apparatus which is insensitive to such small amounts of metallic impurities as might be present in the acid.

Another object of this invention is to provide apparatus which is reasonably insensitive to outside conditions such as small variations in the ambient temperature.

Another object of this invention is that the apparatus be suitable for use by untrained personnel.

Another object of this invention is to provide apparatus which is relatively compact and light in weight but which, at the same time, is rugged and durable.

Other objects and many of the attendant advantages of this invention will be readily appreciated as the same becomes better understood by reference to the following detailed description when considered in connection with the accompanying drawings wherein:

Fig. 1 shows a preliminary chart relative to the NO_2 concentration of an acid, used in obtaining a calibration chart for H_2O and NO_2 concentrations.

Fig. 2 is a second preliminary chart illustrating the percentage of H_2O vs. NO_2 .

Fig. 3 is a preliminary chart relative to the H_2O concentration.

Fig. 4 is a calibration chart upon which the readings on the dial are entered to obtain the H_2O and NO_2 concentrations.

Fig. 5 is a schematic view of a bridge circuit used in the invention.

Fig. 6 is a front elevational view of the face of a dial used in conjunction with the circuit of Fig. 1.

Fig. 7 is a calibration curve used to determine the dial angles in Fig. 2.

In order to analyze a sample of white fuming nitric acid, two values must be determined, the percentage of H_2O and the percentage of NO_2 . The HNO_3 may, if desired, be determined by difference, if metallic impurities are absent or negligible in quantity.

In order to determine two independent variables, it is necessary to make two measurements. Since the classi-

cal titrimetric methods of analyzing acids are unsuitable for field use, it was therefore desirable and convenient, in this case, to measure two physical properties of the unknown acid. It was also necessary that these measurements be of the same type, requiring the same apparatus. A most suitable physical measurement is that of electrolytic conductivity since this is easily and precisely measurable and is relatively insensitive to temperature.

The conductivity of nitric acid is a sensitive function of the water content. There is a minimum in the conductivity curve in the region of 2.5% H_2O and a very broad maximum near 70% H_2O . Small quantities of NO_2 increase the conductivity in the region of 0–10% H_2O to an extent that varies with the H_2O content. It was, therefore, determined that three conductivities would be taken on a sample of acid with the same conductivity cell, one on the original acid and the other two on the original diluted with water to different and known dilutions. If the three conductances were then designated as A, B, and C, two ratios could be derived from them:

$$\frac{A}{B} \text{ and } \frac{B}{C}$$

which would be treated as the two quantities from which the two unknowns (H_2O and NO_2) could be deduced. As the three actual measurements are reduced to two ratios, the constant of the conductivity cell cancels out and, in effect, an automatic calibration of the cell is performed. This procedure, likewise, tends to reduce the temperature effect since the three conductivities might be expected to vary in the same direction with temperature, although not necessarily at the same rate.

The three conductivities are taken upon the following samples, or samples made up in the same proportions: (A) the original acid, (B) 100 cc. of the original to which have been added 5 cc. of H_2O , and (C) 75 cc. of H_2O to which have been added 25 cc. of the original unknown acid.

The finished calibration was visualized as a grid whose coordinates would correspond to the two conductivity ratios

$$\frac{A}{B} \text{ and } \frac{B}{C}$$

crossed by two sets of contour lines corresponding to the H_2O and NO_2 content. It was found empirically that the best spread of these contours would be obtained when the coordinates were

$$\log \frac{M_A}{M_B} \text{ and } \log \frac{M_B}{M_C}$$

(where M corresponds to measured conductivity). In practice, the conversion from resistance to conductivity was omitted and the coordinates finally chosen were

$$\log \frac{R_A}{R_B} \text{ and } \log \frac{R_B}{R_C}$$

(where R corresponds to electrical resistance). For convenience, the contours were given names; a line of constant water content being called an "isodamp" and one of constant NO_2 being called an "isonox."

The calibration was performed at 25° C., using a micro conductivity dip cell with a constant of approximately

$$\frac{R \text{ measured}}{R \text{ specific}} = 10$$

and an Industrial Instruments Co. RC-1 conductivity bridge. Later, the RC-1 bridge was replaced with a bridge designed for the purpose, which is described later in this application. The sample to be measured was held in a test tube just large enough to enclose the dip cell. It was found that with this cell the measured samples need be only 40 cc. in volume.

140 samples of acid were used to cover the field of 0-5% H_2O and 0-2.5% NO_2 . The unit operation involved a series of ten samples, made up as follows: Two 500 cc. samples of nitric acid X and Y were prepared, with fairly similar water content, but with, in one case, little or no NO_2 , and in the other 2.5% or 2.6%. The ten samples were then made up from these as follows:

Sample No.	cc. X	cc. Y	10
0	0	100	
1	10	90	0.0
2	20	80	0.1
3	30	70	0.2
4	45	55	0.3
5	55	45	0.4
6	70	30	0.5
7	80	20	0.6
8	90	10	0.7
9	100	0	0.8

The exact proportions of X and Y in any sample were unimportant, but it was convenient to have the ten spread fairly uniformly over the range.

Each of the ten samples was now diluted appropriately.

(a) Some 40 cc. were set aside in a 50 cc. iodine flask for the A subsample.

(b) 50 cc. were run into a similar flask with an automatic vacuum pipette and 2.5 cc. of H_2O were carefully run in below the surface by means of a burette with a long capillary tip. This was the B subsample.

(c) 30 cc. of H_2O were run into a third flask, and 10 cc. of the acid were added with the automatic pipette. This was the C subsample.

All of the volume measurements were made with reasonable care, but the most critical volume was the 2.5 cc. of H_2O added to B, since a very small error in the amount of water added will lead to a considerable variation in the conductivity.

The samples were then mixed by swirling, and placed in a 25° water bath to equilibrate. The resistance measurements were then made (at the same temperature) and the $\log R_A/R_B$ and $\log R_B/R_C$ parameters were computed and tabulated.

The A subsample was then analyzed for H_2O and NO_2 by highly refined classical methods. The NO_2 content is determined directly, and is probably accurate to 0.01%, but the precision of the determination of the water content by difference, approaches 0.03% (standard deviation), and the water content, therefore, cannot be taken directly from the analytical results.

The assayed H_2O content of the series was therefore plotted against the NO_2 . Under the conditions under which the specimens were made up (all ten from varying proportions of two large samples) it can be demonstrated that the H_2O content must be a linear function of the NO_2 . The best line was therefore drawn through the 20 points (2 assays on each of 10 samples) by the method of least squares, and the H_2O values accepted were those taken from the line and not from the points. Under these circumstances, the standard deviation from the true value of water content was less than 0.01%. The tabulation was as follows:

Table I

Sample No.	NO_2	$\log R_A/R_B$	$\log R_B/R_C$
0	0.00	0.327	1.324
1	0.25	0.288	1.295
2	0.48	0.257	1.266
3	0.74	0.231	1.238
4	0.97	0.208	1.217
5	1.47	0.166	1.173
6	1.72	0.155	1.150
7	1.96	0.139	1.133
8	2.20	0.131	1.110
9	2.45	0.117	1.097

Two curves were now drawn:

$\log R_A/R_B$ vs. NO_2 , and $\log R_B/R_C$ vs. NO_2

These are shown in chart 2 illustrated in Fig. 1. From the smoothed curves and from the NO_2-H_2O line an interim table for the series was constructed as follows:

Table II

NO_2	$\log R_A/R_B$	$\log R_B/R_C$	Percent H_2O
0.0	0.327	1.325	4.45
0.1	0.309	1.312	4.45
0.2	0.294	1.298	4.46
0.3	0.280	1.286	4.47
0.4	0.267	1.274	4.48
0.5	0.256	1.262	4.48
0.6	0.245	1.251	4.49
0.7	0.235	1.241	4.50
0.8	0.225	1.230	4.50
0.9	0.216	1.220	4.51
1.0	0.207	1.211	4.52
1.1	0.198	1.202	4.52
1.2	0.190	1.193	4.53
1.3	0.183	1.184	4.54
1.4	0.176	1.176	4.55
1.5	0.169	1.168	4.55
1.6	0.163	1.160	4.56
1.7	0.157	1.152	4.57
1.8	0.157	1.152	4.57
1.9	0.145	1.137	4.58
2.0	0.139	1.129	4.59
2.1	0.134	1.122	4.60
2.2	0.128	1.115	4.61
2.3	0.124	1.108	4.61
2.4	0.119	1.101	4.62
2.5	0.115	1.094	4.63

The process was then repeated for the next series, and so on until the field was covered. Fig. 2 shows a chart 4 illustrating the coverage attained, each line corresponding to a series of ten samples. (Minus values of H_2O correspond to acid containing excess N_2O_5 .) From the whole series of interim tables, an "isonox" table was constructed, taking one point from each series. A typical "isonox" table is shown in Table III, for the "isonox" corresponding to zero NO_2 content.

40

Table III.—Isonox 0.0

Series	$\log R_A/R_B$	$\log R_B/R_C$	Percent H_2O
40	9.799	1.715	0.65
41	9.803	1.704	0.63
42	0.118	1.603	1.79
43	0.132	1.594	1.79
44	0.261	1.511	2.62
45	0.292	1.482	2.89
46	0.333	1.359	4.09
47	0.322	1.437	3.32
48	0.327	1.325	4.45
49	0.310	1.279	5.09
50	0.276	1.494	2.70
51	9.675	1.732	0.31
52	9.987	1.653	1.18
53	9.417	1.771	-0.29

These values of $\log R_A/R_B$ and R_B/R_C vs. H_2O were then plotted, smooth curves 5 and 6 drawn through them, as illustrated in chart 8 in Fig. 3, and the final $\log R_A/R_B$ and $\log R_B/R_C$ vs. H_2O values taken from the curves.

These values were then plotted upon the final calibration chart, and the isonox drawn in. This was repeated for the other isonoxes; the intersecting isodamps constructed, and the chart completed, as shown at 10 in Fig. 4. It will be noted that on the completed chart the coordinates are labelled "1+A-B" and "B-C" rather than $\log R_A/R_B$ and $\log R_B/R_C$. This is because the special bridge built for the purpose is calibrated in logarithm of ohms rather than in ohms in order to reduce the amount of computation necessary, and in order to get more uniformly spaced dial graduations. The resistance of the A and B samples is between 100 and 1000 ohms, and that of the C is about 14 ohms, using the cell described. Only the mantissa of the logarithm

60

70

75

is on the dial, so that "1+A-B" is defined as "1 plus reading A minus reading B," and B-C is simply "reading B minus reading C." This avoids negative values for the coordinates and makes the use of the chart a completely mechanical process.

The chart was calibrated at 25° C., and it was necessary to determine the effect of the temperature at which the readings were made upon the calibration. Readings were made at various temperatures between 20° and 30° C. on several samples whose composition varied widely within the limits of the field. It was found that since the temperature coefficient of conductivity varied with the composition, no simple temperature correction could be applied, but that the coefficient was sufficiently small that a variation of $\pm 2^\circ$ C. from 25° would lead to an error of less than 0.1% in H₂O or NO₂.

From the values, therefore, of the three resistances, the H₂O and NO₂ content may be determined from the chart.

It is possible to use an ordinary conductivity bridge to make the measurements, but the calculation of

$$\log \frac{RA}{RB} \text{ and } \log \frac{RB}{RC}$$

is inconvenient and may lead to error. In order to satisfactorily use the method of this invention it is necessary to have a bridge with the following characteristics:

(1) It should be capable of measuring any resistance that would be encountered in the test procedure, but should have no superfluous ranges; (2) The dial readings should be applicable to the calibration chart with a minimum of intervening computation; (3) The sensitivity (to variations in resistance) should correspond to the closeness of reading possible with the chart; (4) The dial graduations on the instrument should be as uniformly spaced as possible to facilitate interpolation by an unskilled operator, and there should be only one set of graduations on the dial; and (5) The bridge should be as small, simple in operation and rugged as is consistent with the other qualities.

The bridge, illustrated at 12 in Fig. 5, eliminates the need to calculate

$$\log \frac{RA}{RB} \text{ and } \log \frac{RB}{RC}$$

and has all the other above-mentioned qualities. This bridge 12 comprises a pair of parallel resistances 14 and 16 in series with the cell 18, there being a switch 20 which can be operated to place either resistance 14 or resistance 16 in series with the end resistors 22 and 24 which are themselves connected in series with a potentiometer 26 connected to the conductivity cell through an amplifier 28. The bridge is designed to operate on 110 volt, 60 cycle current, although a battery operated bridge could be substituted, if it were considered desirable. The variable capacitance 30 is provided to sharpen the balance point of the instrument, since with 60 cycle current the imaginary component of the current is appreciable.

Since the "a" and "b" resistances run in the order of hundreds of ohms, and the "c" resistance is usually near 14 or 15 ohms, the bridge is provided with the two resistance ranges 14 and 16, the resistance 14 being the low range and the resistance 16 being the high range. By proper choice of the resistances in the bridge, it is possible to calibrate the bridge so that the dial 32 illustrated in Fig. 6, connected thereto reads directly in the mantissa of the logarithm of the measured resistances, the dial graduations, as indicated by the curve in chart 34, illustrated in Fig. 7, being nearly uniformly spaced. Since only logarithms are being dealt with here it is

necessary only to subtract one reading from another in other to obtain logarithm values to be used on the chart 10.

In practice, a tube, representing the "A" value, is filled with the unknown acid to approximately the same level as the "B" and "C" tubes. The "B" and "C" samples are first stirred, then all three tubes are capped and placed in a water bath filled with water at approximately 25° C. ($\pm 2^\circ$). The bridge is then turned on and allowed to warm up while the samples come to temperature. With the bridge on the high range, with resistance 16 connected, the cell is immersed in the "A" sample, the bridge balanced, and the "A" reading recorded. With the bridge still on the high range, the process is repeated on the "B" sample. It is not necessary to rinse the cell between the "A" and "B" readings. The bridge range is then shifted to the low range with resistance 14 connected, the cell is dipped into the water of the water bath, allowed to drain a moment and then immersed in the "C" sample, after which the bridge is balanced and the reading recorded, taking care to take the reading from the "C" scale on the chart 10.

It should be noted that the "A-B" range on the chart is provided in the form of 1+A-B. This is done because it is desirable to keep this value positive at all times and this would not be the case in the "A-B" range if the value of B is larger than the value of A.

Obviously many modifications and variations of the present invention are possible in the light of the above teachings. It is, therefore, to be understood that within the scope of the appended claims the invention may be practiced otherwise than as specifically described.

What is claimed is:

1. The method of analyzing white fuming nitric acid consisting in dividing the acid into three parts, one part constituting the original acid, a second part constituting a first concentration of the acid in water, and a third part constituting a second concentration of the acid in water, bringing each of said parts to the same temperature, measuring the electrical resistance of each part, determining the ratio of the value of the electrical resistance of the first part to the value of the electrical resistance of the second part, determining the ratio of the value of the electrical resistance of the second part to the value of the electrical resistance of the third part, and, thereafter, evaluating these ratios according to a previously calibrated chart having one series of curves representing the percentage of water in the acid and having another series of curves representing the percentage of nitric dioxide in the acid.

2. The method of analyzing a liquid for a plurality of contaminants consisting of dividing said liquid into a plurality of parts at least equal to the number of contaminants analyzed for, diluting each of said parts except one part with unequal amounts of water to thereby obtain a plurality of dilutions, and measuring the electrical conductivity of said plurality of dilutions.

3. The method of analyzing white fuming nitric acid for nitric dioxide and water consisting of dividing said acid into a plurality of parts, diluting each of said parts except one part with unequal amounts of water so as to form a plurality of dilutions, and measuring the electrical conductivity of said plurality of dilutions.
